(57) **CLAIM**

I claim the ornamental design for a hitch, as shown and described.

DESCRIPTION

FIG. 1 is a perspective view of the hitch;
FIG. 2 is a rear elevational view of the hitch;
FIG. 3 is a first side elevational view of the hitch;
FIG. 4 is a second side elevational view of the hitch;
FIG. 5 is a front elevational view of the hitch;
FIG. 6 is a top plan view of the hitch; and,
FIG. 7 is a bottom plan view of the hitch.
The dashed lines within the figures are shown for illustrative purposes only and form no part of the invention.
